ABSTRACT OF THE DISCLOSURE

A card tray is provided with a track member and a card follower releasably locked in a selected position along the track member.

BACKGROUND OF THE INVENTION

Field of the invention

The invention relates generally to office or library furniture, and particularly to card catalog files.

Description of the prior art

Trays for card catalog files may be provided with card followers fitted with mechanism for releasably locking the followers in selected positions each between the front and the rear of the tray. However, known locking mechanisms for card followers are unduly complicated in design, costly to manufacture and difficult to operate.

SUMMARY

An object of the invention is to provide a card follower characterized by simplicity of construction and the ease with which it may be positively locked in position, released, and then moved to and locked in another selected position.

BRIEF DESCRIPTION OF THE DRAWINGS

FIG. 1 is a fragmentary plan view of a card file tray equipped with a card follower and a track therefor, the bottom and sides of the tray being shown in phantom;

FIG. 2 is a section on line II—II in FIG. 1, looking at the back of the card follower;

FIG. 3 is a section on lines III—III in FIG. 1, looking at the front of the card follower;

FIG. 4 is a section on lines IV—IV in FIG. 1; and

FIG. 5 is an exploded perspective view of the card follower and its track.

The following description is directed to the specific form of the invention illustrated in the drawings. It is not addressed to the scope of the invention, which may be practiced in a variety of forms.

Referring particularly to FIGS. 1 and 3, the card file tray comprises two laterally spaced members 10 forming the bottom of the tray and a pair of laterally spaced members 12 upstanding respectively from the members 10 and forming opposite sides of the tray. The members 10 and 12 are joined together by members (not shown) extending thereacross and respectively forming the front and back of the tray. The bottom, sides, front and back members of the tray may be made of wood, metal or any other suitable material.

In the plane of the tray bottom and disposed between the members 10 is a sheet metal track member 14 which is channel-shaped in transverse section. The track member is provided with a web 16 flush with the undersurface of the members 10, and with a pair of flanges 18 respectively upstanding against the narrow opposed edges of the members 10 and of a width corresponding to the thickness of the members 10. The marginal areas 20 and 22 respectively of the pair of flanges 18 are turned inwardly toward one another, and the marginal area 20 is provided

2

with a series of uniformly spaced open recesses 24 forming between each successive pair thereof a tooth 26. The opposite end portions of the track member are secured respectively to the front and back members of the tray by suitable means (not shown).

5 The track member 14 mounts a follower of the adjustable locking type, generally designated 28, made of metal. The follower comprises a member 30 supporting a plate 32 and means for locking the follower in a selected position along the track member.

10 The base of the support member, designated 34, is of a width for sliding freely between the pair of flanges 18, and longitudinally spaced portions thereof are raised, as by crimps 36, whereby to provide an effective thickness

15 for a sliding fit between the web 16 of the track member and the marginal areas 20 and 22 of the flanges 18. The base 34 terminates in a neck 38 of a width for moving freely between the marginal areas 20 and 22 of the flanges 18 and with a head 40 upstanding from the neck 38. The head 40 is shouldered by crimping, as at 42, whereby to

20 provide a pair of ears 44 respectively on opposite sides of, and forwardly offset from, the main body area of the head, as shown. The forwardly offset ears 44 abut the follower plate 32 and are spot welded thereto for supporting

25 the same. The tray is fitted with a round rod 45 conventionally provided to positively hold the cards, designated C, in the tray. The rod 45 passes freely through openings in the cards and through registering openings 47 and 49 respectively in the follower plate 32 and the main body area of the head 40.

30 The locking means, housing in the space or open ended sleeve between the follower plate 32 and the main body area of the head 40, comprises a trigger 46 pivotally mounted upon a rivet 48 spanning the distance between

35 the follower plate and the main body area of the head 40. One leg of the trigger, designated 50, depends from the pivot 48 and terminates in a portion or tip 52 shaped to normally engage in one of the recesses 24, between a pair of the teeth 26. The other leg of the trigger, designated 54, extends upwardly from the pivot 48 at an angle relative to the leg 50 and terminates in a finger piece 56, as shown.

40 A hairpin type wire spring 58 is provided to constantly urge the tip of the trigger into locking engagement with the track member 16. One leg of the spring, designated 60, is seated against one of the shoulders or abutments 42, while the other leg (designated 62) extends downwardly from a bend 64. The terminal portion of the leg 64 is received in a notch 66 formed in one edge of the trigger

8445 8450 8455 8460 8465 8470 8475 8480 8485 8490 8495 8500 8505 8510 8515 8520 8525 8530 8535 8540 8545 8550 8555 8560 8565 8570 8575 8580 8585 8590 8595 8600 8605 8610 8615 8620 8625 8630 8635 8640 8645 8650 8655 8660 8665 8670 8675 8680 8685 8690 8695 8700 8705 8710 8715 8720 8725 8730 8735 8740 8745 8750 8755 8760 8765 8770 8775 8780 8785 8790 8795 8800 8805 8810 8815 8820 8825 8830 8835 8840 8845 8850 8855 8860 8865 8870 8875 8880 8885 8890 8895 8900 8905 8910 8915 8920 8925 8930 8935 8940 8945 8950 8955 8960 8965 8970 8975 8980 8985 8990 8995 9000 9005 9010 9015 9020 9025 9030 9035

desired position along the track member, whereupon it is released. The trigger immediately pivots in a clockwise direction, as viewed in FIG. 2, under the action of spring 58, and returns to its initial locking position. The tip 52 thereof engages in another of the recesses 24 and is locked in position by the adjacent teeth 26. It will be noted that the leg 50 of the trigger is notched, as at 70, to clear the rod 45.

The extreme simplicity of construction and the ease with which the follower may be positively locked in position, released, and then moved to and locked in another selected position should be noted.

While in accordance with the provisions of the patent statutes, I have illustrated and described the best form or embodiment of my invention now known to me, it will be apparent to those skilled in the art that changes may be made in the form of the device described without departing from the spirit and scope of the invention as set forth in the appended claims.

Having thus described my invention, I claim:

1. In a card tray for a card catalog file, the combination comprising

- (A) a track member, and
- (B) a card follower shiftably mounted on said track member and selectively positionable along the length thereof including
  - (1) an upright follower plate member extending across said track member,
  - (2) means providing a fixed abutment disposed to the rear and facing one end of said follower plate member, and
  - (3) means for releasably locking said follower in a selected position including
    - (a) a trigger plate member connected intermediate the opposite end portions thereof to said follower plate member for pivotal movement relative thereto, the lower extremity of said trigger plate member being received in a selected one of a series of recesses formed in said track member and being thereby locked in position, and
    - (b) a hairpin-type wire spring member with one end thereof seated against said abutment and the other end thereof engaged with said trigger plate member, below the pivotal axis, said spring

member, abutment means and trigger plate member being disposed in immediately adjacent overlying relation to the back of said follower plate member in coplanar relation.

5 2. The combination according to claim 1 wherein the follower plate member is carried by a support member 10 slideable along the track member, said support and follower plate members conjointly form a vertically extending sleeve, the trigger plate member extends from a distance above said sleeve downwardly therethrough to the track member below, said trigger plate member is pivoted on an element extending through said trigger plate member and having its opposite end portions carried respectively by 15 said follower plate and support members, and the spring is disposed within said sleeve between one edge of said trigger plate member and the opposed area of said sleeve.

3. The combination according to claim 1 wherein the follower plate member is carried by a support member 20 slideable along the track member, said support member is provided with a head having a main body part and a pair of laterally spaced shoulders respectively on opposite sides thereof holding said main body part in rearwardly spaced 25 relation to said follower plate member, said follower plate member and head conjointly afford a vertically extending sleeve broad in width and comparatively shallow in depth, the trigger plate member extends from a point above 30 said sleeve downwardly therethrough and is mounted for pivotal movement about an axis disposed between the upper and lower end portions of said sleeve, and said trigger plate and spring members are disposed in side-by-side coplanar relation within said sleeve with one end of 35 said spring member reacting against one of said shoulders and the other against said trigger plate member whereby to yieldably bias said trigger plate member toward the other of said shoulders.
